ALTERNATING ELECTRIC CURRENT RECTIFIER OF THE SELENIUM TYPE

Leslie Ernest Thompson and Alexander Jenkins,
King's Cross, London, England, assignors, by
mesne assignments, to The Union Switch and
Signal Company, Swissvale, Pa., a corporation
of Pennsylvania

No Drawing. Application January 19, 1944, Se-
rial No. 518,886. In Great Britain October 19,
1942

2 Claims. (CL 175—386)

This invention relates to alternating electric current rectifiers of the selenium type comprising a base plate or support provided with a layer or coating of selenium which may contain selenium compounds or other substances, a metallic counter-electrode being applied to the surface of the layer or coating.

The invention has for its object to provide a rectifier of this character having an improved form of counter-electrode and according to the invention this electrode is composed wholly or mainly of indium instead of the metals or alloys hitherto utilized.

A rectifier embodying the invention is found to possess important advantages, in particular the rectification ratio has a satisfactorily high value while the so-called "bottom-bend" characteristic is relatively low.

In carrying the invention into practice, the counter-electrode may be constituted by a layer of metallic indium applied to the selenium layer under considerable pressure. The surface of the metal must however, be as clean and fresh as possible and should preferably be cleaned in any suitable manner before being applied to the se- 25 lenium layer.

The counter-electrode may however, be formed in other ways for example by spraying, volatilising or sputtering.

The favourable characteristics of the improved rectifier above indicated may be still further increased by the addition of relatively small quantities of other metals or substances to the indium so that the counter-electrode is composed, for example, of an indium alloy or mixture containing however a preponderating proportion of indium and the invention may be varied in this and other respects without exceeding its scope.

Having now described our invention, what we claim as new and desire to secure by Letters Patent is:

1. An alternating electric current rectifier of the selenium type described provided with a counter-electrode composed of indium, for the purpose specified.
2. A rectifier comprising a base plate provided with a layer of selenium, and a counter-electrode composed of a layer of indium applied to the selenium layer under considerable pressure.

LESLIE ERNEST THOMPSON.
ALEXANDER JENKINS.
